UNITED STATES PATENT OFFICE

140,180

DESIGN FOR A DOLL OR SIMILAR ARTICLE

Maurice Marossi, New York, N. Y.

Application November 3, 1944, Serial No. 116,118

Term of patent 3½ years

(Cl. D34—4)

To all whom it may concern:

Be it known that Maurice Marossi, citizen of Czechoslovakia, having his first United States citizenship papers, and resident of New York city, in the county of New York and State of New York, has invented a new, original, and ornamental Design for a Doll or Similar Article, of which the following is a specification, reference being had to the accompanying drawing, forming part thereof, and in which,

Fig. 1 is a front view of the doll, embodying my new design;

Fig. 2 is a side view thereof; and

Fig. 3 is a rear view thereof.

I claim:

The ornamental design for a doll or similar article, substantially as shown.

MAURICE MAROSSI.
